I. J. Gumbey

United States Patent Office.

I. F. QUINBY, OF ROCHESTER, NEW YORK.

Letters Patent No. 66,736, dated July 16, 1867.

IMPROVED GOLD-WASHER.

The Schedule referred to in these Letters Patent and making part of the same.

TO ALL WHOM IT MAY CONCERN:

Be it known that I, I. F. QUINBY, of Rochester, in the county of Monroe, and State of New York, have invented a new and useful "Gold-Washer;" and I do hereby declare that the following is a full, clear, and exact description thereof, reference being had to the accompanying drawing, making part of this specification, in which—

The figure is a vertical central section of my invention, showing the relative arrangement of the various parts.

This invention is designed more especially for placer or dry diggings, and its nature consists in the employment of a counter current of clean water passing through the descending gold-bearing sand or earth, whereby all the fine earthy or organic matter is floated off and a thorough separation effected by a suitable revolving beater or agitator.

To enable others to make and use my invention, I will describe its construction and operation.

The base or chamber A is designed to receive the gold and clean sand from the cleansing tube G. It may be provided with several large cocks J, at different elevations to draw, off the fluid portion when the chamber is to be emptied, also a man-hole, H, through which to remove the gold and sand. The induction water-box B, is bolted to the top of the chamber A, and sustains the cleansing tube G by a suitable packed joint, a. The supply water tube T discharges through the outer shell of the water-box B, which is provided with an inner drum or cylinder, d, having a series of slots or openings, i, by means of which the water is introduced from all sides. The tube T leads from a suitable reservoir, R. The cleansing tube or pipe G gradually increases in size from the water-box to its junction with the agitator section or case D, which may be twelve inches, more or less, in diameter. The tube G may be six feet in length, more or less. There is a series of four armed heads, h, keyed or attached by set-screws to the pulley shaft f, which has its bearings in the stuffing-boxes b, and may be provided with a loose and a tight pulley, p and p'. The bell-topped tube E is bolted to the top of case D, and extends upward six feet, more or less, and is provided at the top with a broad spout, S, slightly descending to a collecting or settling-pan, P. The tube E is slightly contracted toward the top, and within this tube is suspended the feeder tube C, having a suitable funnel top. This tube is suspended within the tube E, leaving an annular space between them of one-half inch, more or less. It is of the same taper as E, and extends from the bottom of it to ten feet, more or less, above its top. The water tank R is placed at a suitable elevation above the equalizing or displacing tube E. The pipe T may be about three inches in diameter, and the quantity of water used would depend upon the elevation of the fountain R, being less for a greater height, and *vice versa*. This may be regulated by the gate g. The upper portions of the apparatus may be sustained in a derrick or framework. The gate g is raised by drawing the cord k, which may be extended to the ground, as may also the cord m used for closing the gate. The chamber R being filled, and also the tubes up to the spout S, the earth or sand to be washed is thrown into the funnel y, and descends to the revolving mixer or agitator, by the action of which it is reduced to a fine disintegrated condition, when all the heavier particles of gold or sand will settle through the gentle upward current of water, while all the earthy and organic matter and the very fine particles of gold or gold-dust will be carried up by the current and float off into the settling-pan, shown by dotted lines. When the chamber A becomes filled or nearly so with the washed sand and gold, the water is drawn off and the solid deposits removed to the amalgamator or other apparatus for separating the gold from the sand.

What I claim as my invention, and desire to secure by Letters Patent of the United States, is—

1. Passing the gold-bearing sand or other material to be washed through an upward or counter-current of water, for the purposes herein shown and described.
2. The employment of the agitator, constructed, arranged, and operating in combination with the tubes E, C and G, substantially in the manner and for the purposes set forth.
3. The water-box B, when constructed, arranged, and operating conjointly with the deposit-chamber A, and the supply or induction tube T, and the vertical discharge pipe G, for the purposes set forth.
4. The general construction and arrangement of all the parts, substantially in the manner and for the purposes herein shown and described.

I. F. QUINBY.
